PUMPING APPARATUS

Arthur P. Ruth, Houston, Tex.

Application August 20, 1954, Serial No. 451,203

2 Claims. (Cl. 103—260)

This invention relates to pumping apparatus, and more particularly to pumping equipment of the jet or venturi tube type having jet mechanism of improved construction and arrangement by which increased pumping efficiency may be obtained.

While not limited to such use the invention finds particular application in connection with water supply systems wherein water is pumped from a source into a storage receptacle against the pressure of a column or head of water. Such systems often make use of a closed tank into which water is pumped by some suitable means, such as a pump of the centrifugal or impeller type, whose operation is controlled by the pressure in the tank, and water under pressure from the tank is utilized to operate jet mechanism in conjunction with such a pump.

In pumping systems of this type, as heretofore commonly constructed, venturi tube mechanism is provided which is designed to deliver liquid from the source to the receptacle, and as pressure against which the venturi mechanism operates increases, the volume of liquid which is delivered decreases. Thus, venturi mechanism which is designed to obtain continued delivery of water from the source to the receptacle until the pressure in the receptacle is built up to the desired value, is often ineffective at lower pressures to provide the volume of flow required to maintain the desired supply of water.

Pumping equipment of this type is commonly used in connection with household water supply systems in which a supply tank of relatively small capacity is employed, and when water is withdrawn from such a system in large volumes, as when the system is used for watering lawns or gardens, the pumping equipment is frequently incapable of delivering water in sufficient volume to keep the tank replenished.

The present invention has for its chief object the provision of pumping apparatus of the jet or venturi tube type embodying venturi mechanism of improved construction having means which is operable upon the occurrence of a change in the pressure of the liquid delivered by the mechanism to vary the volume of the liquid delivered.

Another object of the invention is to provide pumping apparatus of the venturi type embodying venturi mechanism which includes means whereby the volume of liquid delivered is greatly increased upon the occurrence of a predetermined decrease in the pressure of the liquid delivered.

A further object of the invention is to provide pumping apparatus of the venturi type having venturi tube mechanism through which liquid is delivered and including a passageway for by-passing a portion of the liquid around the venturi tube, and in which means is provided which is operable upon a decrease in the pressure of the liquid delivered below a predetermined pressure to open the by-pass and upon an increase in the pressure of the liquid delivered beyond a predetermined pressure to close the by-pass.

Another object of the invention is the provision of

2

pumping apparatus of the venturi type having venturi tube mechanism which includes a plurality of venturi tubes arranged in fluid flow relation and including means operable upon a decrease in the pressure of the liquid delivered below a predetermined pressure to cause said tubes to be operated simultaneously and upon an increase in the pressure of the liquid delivered above a predetermined pressure, to cause one of said tubes to become inoperative.

10 A still further object of the invention is to provide pumping apparatus of the venturi type having jet and tube mechanism which is of simple design and rugged construction, capable of long withstanding the continuous use and extreme conditions of exposure to which such devices are likely to be subjected.

The above and other important objects and advantages of the invention may best be understood from the following detailed description, constituting a specification of the same, when considered in conjunction with the annexed drawings, wherein—

Figure 1 is a side elevational view, partly in cross-section illustrating a liquid supply system embodying a preferred form of the invention;

25 Figure 2 is a longitudinal, central, cross-sectional view on an enlarged scale showing the structure of the venturi mechanism of the invention as illustrated in Figure 1;

Figure 3 is a cross-sectional view, taken along the line 3—3 of Figure 2, looking in the direction indicated by the arrows;

30 Figure 4 is a view similar to that of Figure 1 illustrating a somewhat different type of liquid supply system embodying a modified form of the invention;

Figure 5 is a view similar to that of Figure 2, showing the structure of the venturi mechanism of the invention as illustrated in Figure 4; and

Figure 6 is a cross-sectional view, taken along the line 6—6 of Figure 5, looking in the direction indicated by the arrows.

Referring now more particularly to the drawings, 40 wherein like numerals of reference designate the same parts in each of the figures, the invention is illustrated in Figures 1 to 3 in connection with a water supply system which embodies a pressure tank and pump system wherein the venturi mechanism is positioned beneath the water in the tank and is operated in conjunction with a pump of conventional design such as a pump of the rotary impeller type. As shown in Figures 1 to 3, the system includes a pressure tank 10 or other suitable receptacle of conventional construction, into which an inlet pipe 12 leads from any suitable source of water supply such as a well or the like. Within the tank venturi mechanism is located, having a casing, generally designated 14, which has an inlet connected in communication with the inlet pipe 12, and whose outlet is connected to the inlet of a pump, indicated at 16 of suitable construction, such as a pump of the rotary impeller type, located in the tank beneath the level of the water therein and arranged to discharge into the tank. The pump 16 may be operated from any desired power source such as an electric motor 18, which is provided with pressure actuated control mechanism 20 of the usual type. The tank 10 also has an outlet 22 which is located above the level of the pump and inlet pipe.

65 The venturi mechanism of this form of the invention comprises the casing 14, which is of generally tubular configuration having an inlet connection 24 adapted to be connected in communication with the inlet of the pump 16. The casing has an inner web or partition 28 which defines an inlet chamber 30 and a discharge chamber 32. A venturi tube 34 extends through the partition 28 through an opening 36 therein, with the inlet end of the tube

opening into the inlet chamber 30 and the discharge end of the tube opening into the discharge chamber 32. The casing also has an opening 38 leading from the exterior thereof into the inlet chamber 30, through which a jet nozzle 40 extends, whose discharge end is positioned to discharge into the inlet end of the venturi tube 34.

The partition 28 is also shaped to form a valve cage 42 between the inlet chamber 30 and discharge chamber 32, which cage has an opening 44 providing a valve seat. A valve, such as a ball valve 46 is movably disposed in the cage 42 in position to move into and out of closing contact with the seat 44, and means is provided, such as the snap ring 48 for preventing the ball 46 from escaping from the cage into the discharge chamber 32. The arrangement of the cage and valve is such that when the pressure of fluid in the inlet chamber 30 is greater than the pressure of fluid in the discharge chamber 32, the valve 46 will be unseated to allow fluid to flow through the cage into the discharge chamber, but upon an increase of pressure in the discharge chamber beyond a predetermined limit above the pressure in the inlet chamber the valve will be closed.

In the operation of the above described form of the invention, upon operation of the pump 16, water will be drawn through the inlet pipe 12 and through the venturi mechanism to be discharged by the pump into the tank. During such operation water under pressure may flow from the tank through the jet nozzle 40 and will be discharged through the venturi tube 34 to cause water to be drawn from the inlet chamber 30 through the venturi tube into the discharge chamber 32 to assist the pump 16. When the pressure in the tank is low, the pump 16 will cause a substantial reduction in the pressure in the outlet chamber 32 below the pressure in the inlet chamber 30 and the valve 46 will be moved to open position to allow a relatively large volume of water to flow through the mechanism into the tank. When the pressure in the tank rises to a predetermined value, however, the pump 16 will be ineffective to maintain a sufficiently low pressure in the outlet chamber 32, and the valve 46 will thereupon move to closed position. Due to the higher pressure which has then been built up in the tank, however, the jet nozzle 40 and venturi tube 34 will continue to operate, delivering water at a reduced volume until the pressure in the tank reaches the limit at which the pumping apparatus will function.

By this arrangement it becomes possible to provide a water supply system which is capable of operation to supply a relatively large volume of water at a somewhat reduced pressure, and which will also supply water at a somewhat higher pressure when the volume required is smaller. Thus, a water supply system, in which water is provided at a pressure of 40 to 50 pounds per square inch, in the volume usually required for ordinary household use, may be adapted to supply water at a somewhat lower pressure in greater volume, such as might be required for watering of livestock or gardens. Moreover, by the use of the system and apparatus of the invention the replenishment of the supply of water in the tank may be accomplished much more rapidly than by the use of conventional pumping apparatus of this type, thus making more effective and efficient use of the available power.

A somewhat different form of the invention is illustrated in Figures 4, 5 and 6, wherein the venturi mechanism is located outside of the tank 10, or other receptacle, at some point remote therefrom, such as a well indicated at W. In this form of the invention an inlet pipe 12' is connected in communication with the discharge connection of the venturi mechanism and extends into the tank 10' wherein it is connected to the inlet of the pump 16'. The tank 10' also has an outlet pipe 50 which is connected in communication with the interior of the tank beneath the level of the water therein and through which water under pressure is supplied to the jet nozzle of the venturi mechanism for actuation thereof.

The venturi mechanism of this form of the invention comprises a casing 14' having an inlet connection 24' and an outlet connection 26', which outlet connection is connected to the inlet pipe 12' through a secondary venturi tube 52. The casing 14' has an internal partition 28' which defines an inlet chamber 30' and an outlet chamber 32'. A primary venturi tube 34' extends through the partition 28' through an opening 36' therein, with the inlet end of the tube opening into the inlet chamber 30' and the outlet end thereof positioned to discharge into the inlet end of the secondary venturi tube 52. The casing also has an opening 38' which leads into an interior passageway 54' therein separate from the inlet chamber 30' and into which the pressure supply pipe 50 is threaded, there being an opening 56 in the partition 28' through which a jet nozzle 40' extends whose inlet end is in communication with the passageway 54', and whose discharge end is positioned to discharge into the inlet end of the primary venturi tube 34'.

The partition 28' also has a portion 58 surrounding the primary venturi tube 34' which is provided with an annular groove 44' forming a valve seat. The portion of the casing beyond the valve seat 44' and between the same and the inlet of the secondary tube 52 forms a valve cage 42' within which a valve 46' is movably disposed, which valve takes the form of an O-ring. The inlet end portion of the secondary venturi tube 52 together with the valve cage 42' constitute a discharge chamber corresponding to the discharge chamber 32 of the previously described form of the venturi mechanism of the invention.

The operation of this modification of the invention is similar to that of the previously described form of the same, the venturi mechanism being located in the well W instead of within the pressure tank. When the pressure tank 10' falls to a predetermined lower value the pump 16' comes into operation to draw water from the well through the venturi mechanism and the inlet pipe 12' and discharge the same into the tank. When the pressure within the tank is below a predetermined pressure the pressure in the outlet chamber of the venturi mechanism will be lower than that in the inlet chamber 30 and the valve 46' will move to open position, as seen in dotted lines in Figure 5, whereupon a relatively large volume of water may flow through the mechanism to the tank. Water under pressure also flows from the tank through pressure supply pipe 50 to the jet nozzle 40' to actuate the primary venturi tube 34' to draw additional water through the venturi mechanism. Upon such actuation of the primary venturi tube this tube acts as a jet nozzle to actuate the secondary venturi tube 52, whereby water is drawn from the inlet chamber 30' and discharged into the inlet pipe 12'. When the pressure within the tank 10' reaches a predetermined upper value, the pressure within the discharge chamber of the venturi mechanism will be such that the valve 46' will be moved to closed position, as shown in Figure 5, and the secondary venturi tube will no longer be actuated, but water will still be supplied to the tank through the actuation of the primary venturi tube, until the pressure in the tank rises to a point at which the pump 16' is no longer operated.

In this manner a large volume of water may be quickly supplied to fulfill a large demand such as in the case where the water is used for irrigation purposes, and when the water is no longer required in large volume the tank will be quickly replenished to supply ordinary demands at a somewhat higher pressure.

Additional venturi tubes may be employed, arranged in the same manner as described above, to provide a multi-stage pumping system, if desired.

The pumping apparatus may, of course, be employed with other types of supply tanks or receptacles than those illustrated herein whether open or closed.

It will thus be seen that the invention constructed and operated in the manner described above provides pumping apparatus which is of simple design and economical

manufacture, having few parts likely to become worn or out of order and in which the parts are easily replaceable for purposes of maintenance and repair.

While the invention has been disclosed herein in connection with certain specific embodiments of the same, it will be understood that this is intended by way of illustration only and that numerous changes can be made in the construction and arrangement of the various parts without departing from the spirit of the invention or the scope of the appended claims.

Having thus clearly shown and described the invention, what is claimed as new and desired to secure by Letters Patent is:

1. Pumping apparatus comprising a casing having an inlet and an outlet, a first venturi tube in the casing positioned to receive fluid from said inlet and to discharge the same toward said outlet, nozzle means in the casing having an inlet end in communication with a source of fluid under pressure and positioned to discharge such fluid in a direction to cause fluid to flow through said first venturi tube from said inlet toward said outlet, said casing having a portion forming a passageway in communication with said inlet and said outlet exteriorly of said first venturi tube, valve means in the casing operable to close said passageway against the flow of fluid from said outlet toward said inlet, and a second venturi tube positioned to receive fluid from said outlet and whose inlet end extends into said passageway in position for engagement by said valve means to limit opening movement of said valve means.

30

2. Pumping apparatus comprising a casing having an inlet and an outlet, a first venturi tube in the casing positioned to receive fluid from said inlet and to discharge the same toward said outlet, nozzle means in the casing having an inlet end in communication with a source of fluid under pressure and positioned to discharge such fluid in a direction to cause fluid to flow through first venturi tube from said inlet toward said outlet, said casing having a portion forming with said first venturi tube an annular passageway in communication with said inlet and said outlet exteriorly of said first venturi tube, means forming an annular valve seat in the passageway, an annular valve member movably positioned in the passageway for movement in one direction to engage said seat to close the passageway and in the other direction to open the passageway, a second venturi tube threadably connected to the casing in position to receive fluid from said first venturi tube and having an inlet end face positioned for engagement with said valve member to limit opening movement of the valve.
